UNITED STATES PATENT OFFICE.

LEWIS P. R. LE COMpte, OF PORTLAND, OREGON.

FRUIT-JAR COVER.

SPECIFICATION forming part of Letters Patent No. 360,165, dated March 29, 1887.

Application filed February 4, 1887. Serial No. 226,572. (No model.)

To all whom it may concern:

Be it known that I, LEWIS P. R. LE COMpte, of Portland, Multnomah county, Oregon, have invented certain new and useful Improvements 5 in Fruit-Jar Covers, of which the following is a specification, reference being had to the accompanying drawings, forming part hereof, in which—

Figure 1 is a top plan view of my invention. 10 Fig. 2 is a side elevation showing a jar and cover made in accordance with my invention, the cover being locked on the jar; and Fig. 3 is a similar view showing the bails down and the cover unlocked.

15 Like letters of reference mark the same parts wherever they occur in the several figures of the drawings.

20 My invention relates to fruit-jars and the covers therefor, and has for its object to furnish a jar and cover in which any desired pressure can be brought to bear upon the cover in hermetically sealing the same, and in which 25 said pressure is properly distributed in several points in both jar and cover.

25 Referring to the drawings by letter, A is an ordinary fruit-jar, which is provided with a pair of bails, B C, each of which has an inward-pointing end, $b' b' c' c'$, on each side of the jar. These bails may be varied in shape, it being necessary 30 that they shall be secured at their ends to the jar and pass over the top D. The points of fastening of the ends $b' b' c' c'$ of the bails to the jar are such that the ends of each bail are not diametrically opposite to each other, but 35 are so situated that the points on the same side of the jar where the ends $b' c'$ are secured are at a considerable distance apart. The bails B C, when in securing position, as shown in full lines in Figs. 1 and 2, pass across the top 40 in parallel lines at substantially the same distance apart.

D is the top of the jar, the central portion of which projects slightly into the mouth of the jar, and it has an annular flange, which 45 rests on the top of the jar, a packing-ring, E, being interposed. On its upper surface the top D is provided with a vertical rib, F, which may be formed integrally with the top, or may be secured thereto in an undercut groove, G, 50 as shown, or in any other desired manner. The upper surface of this rib curves or inclines downward from its highest central point to the ends of the rib at the edges of top, and is provided with serrations $f' f'$. The outer edge of 55 the top may also be provided with serrations.

When it is desired to close the jar, the packing-ring is placed on top of it, the top put thereon in position, so that its rib F stands at right angles with the central portions of the bails B and C, and the bails pressed toward 60 each other.

As before stated, the ends b and c and b' and c' are about sixty degrees apart, leaving two spaces of about one hundred and twenty degrees each outside these ends. These spaces 65 are substantially bisected by the rib F at the points $b^2 c^2$, so that when the bails are pressed toward each other and moved up the double inclined rib F, engaging in the serrations $f' f'$, pressure will be exerted specially at the six substantially equidistant points $b b' b^2 c c' c^2$, and if more pressure is needed at any particular point of the jar and top, one of the bails will pass farther up the inclined rib than the other, and thus secure the needed perfect contact and 75 equally-distributed compression of the packing.

I am aware that it is not new to provide a jar with a bail which engages an incline on the top, and consequently do not make claim to 80 such a construction.

What I claim as new, and desire to secure by Letters Patent of the United States, is—

1. A fruit-jar having two bails pivoted thereto, in combination with a cover provided 85 with two inclined notched surfaces to engage said bails, as set forth.

2. A fruit-jar having two bails pivoted thereto, in combination with a cover provided with a central diametrically-arranged rib projecting upward from said cover and having 90 notched surfaces inclined downward from the center of the cover, as set forth.

3. In combination, the jar A, having bails B and C pivoted thereto, one on each side of 95 a line drawn centrally through the jar, and the cover E, having rib F projecting upward therefrom, the surfaces f and f' of said rib being inclined downward from the center toward the opposite sides of the cover, substantially 100 as and for the purposes set forth.

In testimony that I claim the foregoing as my own I have hereunto signed my name in the presence of two subscribing witnesses.

LEWIS P. R. LE COMpte.
